SPECIFICATION forming part of Design No. 23,567, dated August 21, 1894.

Application filed July 28, 1894. Serial No. 518,883. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of flambeau or torch-like ornaments with two sprays of 10 leaves attached and arranged on either side of said ornaments in the form of an open wreath, and festoons of small ornaments connecting the flambeau or torch-like ornaments as represented in the accompanying drawing. Between 15 said ornaments are placed small ornamental figures at certain distances apart and form part of the design. The border or up-

per portion of the design is formed of the same flambeau shaped ornaments with the sprays of leaves attached in the form of an open wreath with festoons of small ornaments and two crossed sprays of leaves crossing said festoons as shown in the drawing.

What I claim is—

1. The design for wall paper herein shown and described.
2. In the design for wall paper the border herein shown and described.

Witness my hand this 26th day of July, 1894.

CHARLES BOOZE.
